The cooling oil in large electrical transformers is purified, by having sorbed water and gases removed, by means of a vacuum treatment vessel permanently plumbed to the transformer. The desorbing treatment is carried out while the transformer is live, so that the oil needs little or no extra heat supplied before it can be treated.

ELECTRICAL TRANSFORMERS

This invention relates to big electrical transformers of which the windings are immersed in a dielectric oil housed in a container.

The dielectric strength of such an oil is appreciably reduced by the presence in it of water, gas or particulate impurities. This leads to inefficient operation of the transformer as its losses increase with time as the oil becomes increasingly adulterated as water and gas from the atmosphere are absorbed by the oil. While solid impurities can be removed by filters having pores of appropriate size, absorbed gases and water vapour have to be removed by a desorption process.

It is known to treat electrical oils intermittently by coupling up the transformer container at chosen intervals to a mobile treatment unit employing filters, electrical or other heaters, and vacuum degassing apparatus. The treatment unit consumes a lot of power in heating the oil up to its treatment temperature, and takes a long time because of the care which has to be taken during the heating process to limit the temperature which the oil reaches so as to avoid thermally decomposing the oil. Immediately prior to the treatment, and during all the time that the treatment is taking place, the transformer is out of commission, and hence elaborate and expensive measures have to be taken to make up for this.

The present invention aims at enabling transformer oil to be treated while the transformer is live, but obviating, or at least reducing, 'down-time' of the transformer.

Accordingly the present invention provides an oil-insulated electrical transformer which is as claimed in the appended claims.

The present invention will now be described by way of example with reference to the accompanying drawing, which is a diagrammatic view of a transformer of the present invention.

A transformer casing 2 houses the windings and insulating oil of the transformer, electrical connection to the transformer windings being effected by means of insulating bushings 4.

Extending from the lower part of casing 2 is a conduit 6 leading through a valve 8 to a filter vessel 10 which is designed to remove from the oil at least a high proportion, if not all, of any solid particles in suspension in, or entrained by, the oil stream. The filtered oil stream passes along conduit 6 and through a flow-control valve 12 to the upper part of a vacuum treatment vessel 14, having a central compartment 16 in which are packed Raschig rings or other column fillers 17 over which the oil to be treated flows in a thin film. In so doing, the oil is subjected to vacuum by means of a vacuum pump 18 driven by an electric motor 20. Positioned in the lower part of vessel 14 is a level-sensing switch 22.

The conduit 6 leading from the bottom of vessel 14 passes through an oil pump 24 and a permanent magnet filter 26 to a discharge valve 28. From valve 28 the treated oil passes through a valve 30 before reentering the interior of casing 2.

Associated with the apparatus is a control unit 32 which is connected to valve 8; motor 20; a vacuum gauge 21; level-sensing switch 22, and pump 24.

By means which do not form part of the subject-matter of the present application, and which are there-

fore not described in further detail, the control unit 32 acts to open valve 8 when the level of contamination of the oil in chamber 2 reaches a chosen value. It is also effective to monitor the degree of vacuum in vessel 14 and to start the vacuum pump when the pressure in the interior of vessel 14 rises to too high a value. It is also effective to switch the vacuum pump off when the pressure in vessel 14 has fallen to a chosen minimum level.

Control unit 32 is also effective to energise pump 24 when the level-sensing switch 22 indicates that there is sufficient volume of vacuum-treated and filtered oil in the bottom of the vessel 14.

The discharge valve 28 can be operated either automatically or manually as need arises.

For the treatment process to be successful, it is necessary for the temperature of the contaminated oil to be treated to be raised to about 45°-65°C. At this temperature the surface tension of the oil is sufficiently low to allow any absorbed gases or vapours to be desorbed by the application of a suitable degree of vacuum in vessel 14. In accordance with the present invention, the oil is raised to this treatment temperature by the waste heat normally released by the transformer windings when it is operating. If the oil does not normally reach the desired treatment temperature, or if it falls below this temperature under adverse weather conditions, it is within the purview of the present invention to incorporate an auxiliary heater 34 in conduit 6 before filter 10.

In view of the relatively large mass of oil required to be treated, the heater will be of insufficient capacity to heat all the oil in casing 2 from ambient temperature to the treatment temperature, so that the major proportion of the heat necessary would be supplied by the transformer windings. This leads to a substantial reduction in the expense of the degassing equipment, in that the heater can be of very low rating compared with that necessary for existing mobile servicing units.

The degree of contamination of the oil can be monitored either continuously or intermittently, and the results of the monitoring can be used to cause control unit 32 to switch on the treatment unit when the degree of contamination has risen to a specified level. However, it might be desirable in some circumstances to keep the treatment unit operating continuously so that any contaminants are removed more or less immediately after they appear in the oil.

The choice between these two conditions is made on considerations which do not effect the mode of operation of the present invention, and so will not be described further.

I claim:

1. An oil insulated electrical transformer including a casing having an outlet permanently communicating its interior with vacuum degassing apparatus for treatment of the oil while the transformer is live, means for feeding oil to the degassing apparatus, and returning treated oil to the interior of the casing, either continually or intermittently, the degassing apparatus including a compartment containing packed column fillers over which the oil can flow in thin films, said compartment being connected to a vacuum pump, a control unit operatively connected between the compartment and vacuum pump to turn the vacuum pump on when the pressure in the compartment is above a chosen maximum; and to turn the pump off when the pressure is below a chosen minimum, a valve located at the outlet of the

casing and controlling flow of oil from the interior of the casing, said control unit opening the valve when the contamination in the oil in the casing reaches a chosen level, and a second valve located at the inlet of the casing and controlling the flow of treated oil toward the interior of the casing.

2. A transformer as claimed in claim 1, in which a filter vessel is located between the outlet of the casing

and the inlet of the degassing apparatus, an oil pump being located between the outlet of the degassing apparatus and the inlet of the casing, said the control unit energising the oil pump when the amount of treated oil in the degassing apparatus reaches a chosen level, and a permanent magnet filter being located between the outlet of the oil pump and the inlet of the casing.
